ORTHOPEDIC BRACE

Elmer M. Arluck, New York, N.Y., assignor to Thermo-Mold Medical Products, Inc., New York, N.Y.

Filed Apr. 19, 1976, Ser. No. 678,255

Term of patent 14 years

Int. Cl. D24—04

U.S. Cl. D83—1 J

FIG. 1 is a top plan view of an orthopedic brace showing my new design;

FIG. 2 is a bottom plan view thereof;

FIG. 3 is a side elevation thereof;

FIG. 4 is a side elevation thereof taken from the opposite side as FIG. 3;

FIG. 5 is a left-end elevation thereof; and

FIG. 6 is a right-end elevation thereof.

I claim:

The ornamental design for an orthopedic brace, as shown.
